ATTORNEY.

UNITED STATES PATENT OFFICE.

EDWARD W. CLARK, OF LOS ANGELES, CALIFORNIA.

PISTON AND METHOD OF MAKING THE SAME.

1,281,765.

Specification of Letters Patent. Patented Oct. 15. 1918.

Application filed October 13, 1917. Serial No. 197,348.

To all whom it may concern:

Be it known that I, EDWARD W. CLARK, a citizen of the United States, residing at Los Angeles, in the county of Los Angeles and State of California, have invented new and useful Improvements in Pistons and Method of Making the Same, of which the following is a specification.

My invention relates primarily to pistons for internal combustion engines, but the same may be used in connection with steam engines as well with a like degree of success and efficiency, the novelty of my improvements including a piston having a skirt portion of cast iron, preferably, so formed that a minimum thickness may be provided and the major portion thereof being machined for providing a minimum weight, without detracting from the efficiency of the piston.

In order that the above objects may be carried out it is necessary that the head of the piston should be separately formed and attached to the skirt portion, both ends of the skirt being open and access being thus afforded to the interior thereof for machining the inner periphery of the skirt, which, in the ordinary form of piston is inaccessible for this purpose.

The head and skirt being separately formed, may be made of separate materials, the skirt, as stated, being preferably of cast iron, and the head of steel, thus rendering the head capable of being turned down to a very thin cross section and yet providing ample strength and resistance to the impact of the explosions in the engines.

A further object of this invention is to provide means for reinforcing the head and for securely attaching the same to the skirt subsequent to the separate finishing of these elements, so that a permanent union of the two parts may be made.

I am aware that patents have been heretofore granted for pistons having separable and detachable heads of different material from that used in the skirt portion, one form of such device being disclosed in a former invention of mine for which I have made application for Letters Patent of the United States, filed November 18, 1915 Serial Number 62,137, and allowed August 29, 1916; a patent therefor having been granted to me on April 3, 1917, Number 1,221,419. The present invention, however, is an improvement over my former invention, the

several features of which will be hereinafter set forth and described in detail.

Having in mind the above and other objects, I prefer to carry out the objects mentioned by means of the structure illustrated in the accompanying drawings, in which:

Figure 1 is a plan of my improved piston, partly broken away at the top;

Fig. 2 is a bottom view of the same. 65

Fig. 3 is an elevation of the same, the major portion of which is in section on a plane longitudinally of the wrist pin.

Fig. 4 is an elevation, partly in section transversely of the wrist pin and at right angles to Fig. 3. 70

Fig. 5 is a perspective view of the piston head, in inverted position.

Similar characters of reference are employed throughout the specification following and in the several views of the drawings for indicating the same and like parts. 75

The preferred embodiment of my improved piston which is shown in the drawings comprises two separate and distinct parts, namely, a skirt 10 of cylindrical formation initially and normally open at both ends for affording access to the interior of the piston for a finishing tool, and a separate head 11 which is adapted to be inserted in the upper end of the skirt subsequent to the finishing operation and permanently held therein in the manner hereinafter described. The general appearance of the skirt 10 is similar to that of pistons in general use in internal combustion engines, with the exception that the upper and lower ends thereof are provided with a greater thickness of metal than the central portion, as indicated at 12 and 13, and a pair of transversely disposed internal and oppositely formed bosses 14 and 15 are cast integrally with the skirt for receiving a wrist pin 16. Bores 17 are formed in the bosses 14 and 15 to fit the wrist pin as in the usual cases, and a connecting rod end 18 may be pivotally held on the wrist pin by means of a bushing 19, as shown in Fig. 3. 85

The skirt 10 is preferably formed of cast iron of a high grade, this being the best metal for general use in cylinders, and as stated, the skirt is integrally cast with the walls thereof of about a uniform thickness, after which the skirt may be turned down 110 in a lathe to a minimum thickness as shown, thus reducing the weight of the piston to a

minimum and correspondingly reducing the amount of power necessary to move the pistons in the cylinders and rendering the motor capable of greater power to be applied 5 to the load thereon.

On the inner ends of the bosses 14 and 15 I provide ribs 20 and 21 which are circular in cross section and extend upwardly in the skirt 10 to a point near the top where a circular rib 22 is formed and a transverse rib 23 connects the same with a central boss 24. The ribs 20, 21, 22 and 23 and the boss 24 are integral with the skirt 10 and serve as a support for the head 11, which I will now 15 describe.

The head 11 is of cup formation with a web portion 25 forming a top and a circular side 26 adapted to have threads 27 formed thereon so that the same may be threaded 20 into the upper end of the skirt 10 in an inverted position as shown in the drawing, the bottom of the web portion thereof, when the head is in position in the skirt, resting upon the circular rib 22, as shown. The 25 upper end of the skirt 10 has an internal shoulder 28 formed therein, below which the lower end of the head 11 projects when the web thereof rests upon the rib 22 as stated, and the edge of the circular side 26 30 is adapted to be rolled by suitable means over this shoulder so as to rigidly clench the head and hold the same in position firmly between the rib 22 and shoulder 28. Ordinary piston rings 29 are positioned in the 35 usual grooves formed on the exterior of the piston skirt, as shown.

It will be understood from the description of the structure of my device that the head 11 being formed preferably of steel may be 40 made in a single stamping operation of an integral sheet of steel, and by means of the open ends of the skirt 10 a turning tool may be easily inserted in each end of the skirt for reducing and finishing the walls of the piston 45 ton to a minimum thickness, thus providing a minimum weight and increasing the efficiency of the piston. The central portion of the skirt, as shown, may be turned down on the outside instead of the inside 50 for providing substantially a uniform thickness of metal to compensate for the finishing of the inside at the end portions.

It will be also understood that the head 11, when clenched in the skirt as described, 55 will be practically integral with the skirt and by means of the supporting ribs formed integral with the walls of the skirt additional supports will be provided at points near the center of the skirt for reinforcing 60 the head against damage or deflection due to shock from successive explosions. If found to be desirable or necessary, the web of the head may be riveted to the boss connected to the circular rib 22 so that no bending 65 or warping may result from continual

use. The space around the vertical ribs in the skirt will be ample to permit the insertion and use of a tool for finishing the interior of the walls. The original skirt casting should be sufficiently thick to permit the 70 turning off of surplus grain from the metal so that no defects will be left in the casting and a true circle may be preserved under all strains in the walls. The positions of the vertical supporting ribs relative to the walls 75 of the skirt serve to equalize the strain on the wrist pin under all conditions, and thus prevents excessive wear on the pin and connecting rod bearings. Other advantages will be apparent. 80

What I claim is:

1. A piston comprising a composite structure including a skirt open at both ends and threaded to receive a head for closing the working end thereof, and a head threaded 85 into said skirt and having its edges formed over and in permanent contact with an abutment on the interior of said skirt.

2. A two-piece piston comprising a cast iron skirt having an opening at both ends, 90 the upper end thereof being threaded and a shoulder provided at the lower end of the threads, and a head having a web for closing the working end of the piston and an extension adapted to be threaded into said skirt, 95 the end of said extension being formed over said shoulder.

3. A piston comprising separately formed skirt and head elements, said head being insertible in the working end of said skirt and 100 the end thereof being formed over an abutment in said skirt, and a plurality of piston ring grooves being provided in said skirt element.

4. A piston comprising a separately formed 105 head and skirt, said head being insertible in said skirt and being threaded into the upper end of said skirt, and said skirt having an annular shoulder formed therein, the lower end of said head being formed over 110 said shoulder for permanently holding said head and skirt together for operation.

5. A piston comprising an internally threaded skirt having a shoulder formed 115 therein, and a head having an extension threaded thereinto and formed over said shoulder.

6. A piston having separately formed head and skirt members, said skirt having 120 wrist pin bearings formed therein, and an annular shoulder thereabove, said head having a threaded extension secured in said skirt and overlapping said shoulder.

7. A piston comprising separately formed head and skirt members, said skirt having 125 integrally formed wrist pin bearings and means extending from said bearings for supporting said head.

8. A piston having separately formed head and skirt members permanently held 130

together, said skirt having integrally formed wrist pin bearings and supporting ribs formed on said bearings for reinforcing said head.

5 9. A method of making pistons consisting of separately forming and finishing a head and a skirt member, internally threading one end of said skirt and externally threading said head for attachment together, providing an abutment internally of said skirt, and forming the inserted end of said head over said abutment.

10 10. A method of making pistons consisting of separately forming a head and a skirt of separate materials, threading the adjacent ends of said head and skirt for attachment together, said skirt having an annular shoulder formed therein, inserting said head into said skirt, and forming the end of said head over said shoulder, for permanently holding said members together.

15 11. A method of making pistons consisting of separately forming a head and a skirt of different materials and attaching the same together for operation, said skirt being open at the ends and having an annular shoulder therein near the end of said head, and forming the inserted end of said head over said shoulder.

20 12. A piston comprising separately formed skirt and head members, said skirt member being open at both ends and having an integrally formed abutment at the working

end thereof, and said head member being insertible in the end of said skirt member and adapted to rest upon said abutment. 35

13. A piston comprising separately formed head and skirt members, said head member being insertible in and having its edges adapted to be formed over an abutment in said skirt member, and said skirt member having an integrally formed abutment for engagement with said head member.

14. A piston comprising separately formed head and skirt members, said head member being insertible in the working end of said skirt member and said skirt member having means formed integrally therewith for holding said head member against inward movement and said skirt being recessed at the inner end of said head to prevent movement thereof outwardly of said skirt member. 45

15. A piston comprising separately formed head and skirt members, said head member being insertible in and serving to close the working end of said piston, and having its edges formed over a shoulder on the interior of said skirt member, and said skirt member having an integrally abutment 55 engaging the inner portion of said head member, said shoulder and said abutment serving to prevent the displacement of said head member from said skirt member. 60

EDWARD W. CLARK.
